UNITED STATES PATENT OFFICE.

HENRY EAST AND FRED LLEWELLYN TURNER, OF BIRMINGHAM, COUNTY OF WARWICK, ENGLAND.

WATCH-BOW FASTENER.

SPECIFICATION forming part of Letters Patent No. 412,844, dated October 15, 1889.

Application filed September 3, 1888. Serial No. 284,484. (No model.)

To all whom it may concern:

Be it known that we, HENRY EAST and FRED LLEWELLYN TURNER, subjects of Her Majesty the Queen of Great Britain, both residing at Birmingham, in the county of Warwick, England, have invented certain new and useful Improvements in Securing Watch-Bows to the Pendants of Keyless and other Watches, of which the following is a specification.

10 This invention consists of the improvements herein described in securing together the bows and pendants of keyless and other watches, so as to prevent the watch and pendant being wrenched from the bow, but allowing 15 of the bow and pendant being readily taken apart when required for repairs.

On the accompanying drawings, Figure 1 is an elevation of a watch-bow and pendant constructed according to this invention. Fig. 2 is a sectional elevation, and Fig. 3 is a sectional plan, of the same. Fig. 4 is a cross-section of the upper part of the same. Fig. 5 is a separate view of the bow. Fig. 6 represents in vertical section and in plan the 25 pendant of the same separately, and Fig. 7 shows separate views of the filling-up part of the pendant.

The same letters of reference indicate corresponding parts in all the figures.

30 Referring to the figures, A is the pendant, and B is the bow or ring. The ends b' of the bow or ring B are, for the purpose hereinafter described, made larger than their necks b^2 , which can be done either by reducing the 35 necks, as seen in Fig. 5, or by upsetting the ends of the bow, so as to form heads. In the pendant A are two circular recesses c' opposite each other, in which the necks b^2 of the bow fit, and these recesses extend as longitudinal

slots c^2 to the top of the pendant. 40 This is shown more clearly by Fig. 6. The ends of the bow can be inserted in the open ends of the longitudinal slots c^2 and pushed down to the circular part c' , where the bow is maintained by a tubular filling-up piece D, 45 which fits inside the pendant and has two projecting parts $d' d'$, which fit in the longitudinal slots c^2 , the lower ends of the parts $d' d'$ being hollowed to fit onto the necks of the bow. 50

The filling-up piece D is fixed in the pendant A by any convenient means, such as by the two wire pins e, which pass through the pendant and the filling-up piece. By the ends of the bow being larger than the recesses c' 55 in the pendant the bow cannot be wrenched from the pendant, as it can only be removed therefrom by first removing the filling-up piece D.

What we claim as our invention, and desire 60 to secure by Letters Patent, is—

In combination, a watch-bow having headed ends integral therewith, a pendant provided with side slots extending from the edge thereof and adapted to engage the necks of the 65 bow, and a removable filling-up piece fitting in the pendant and provided with projecting parts which fit in the side slots and secure the end of the bow therein, all substantially as set forth. 70

In testimony whereof we have each signed in the presence of two subscribing witnesses.

HENRY EAST.

FRED LLEWELLYN TURNER.
